DOOR LATCH

Filed April 14, 1928

Frederick A. Cox
INVENTOR
BY
Victor J. Evans
ATTORNEY

UNITED STATES PATENT OFFICE

FREDERICK AVERY COX, OF CHICAGO, ILLINOIS

DOOR LATCH

Application filed April 14, 1928. Serial No. 270,092.

This invention relates to certain novel improvements in door latches and has for its principal object the provision of an improved construction of this character which will be highly efficient in use and economical in manufacture.

It is among the objects of my invention to provide a latch for doors which may be expeditiously inserted in position which will 10 be arranged such that it will effectively prevent the opening of a door.

Another object of the invention is to provide a latch of the foregoing character which will be arranged such that it may be nested 15 into a compact package when not in use.

A still further object of the invention is to provide a device of the foregoing character which will embody a portion which may be inserted in the latch bolt opening of the 20 door jamb and which will be arranged such that another portion will engage the surface of the door in the direction in which the door is to be opened and to provide means for inter-connecting these portions which 25 will prevent displacement thereof.

Other objects will appear hereinafter.

The invention consists in the novel combination and arrangement of parts to be hereinafter described and claimed.

The invention will be best understood by 30 reference to the accompanying drawings, showing the preferred form of construction and in which:

Fig. 1 is a horizontal sectional view depicting the preferred form of construction 35 for my latch in installed position with respect to a door;

Fig. 2 is a side elevational view of one of the elements of my improved latch;

Fig. 3 is a side elevational view of another 40 element of my latch; and

Fig. 4 is a plan view depicting the elements shown in Figs. 1 and 2 in their nested 45 inoperative relation.

In the drawings I have illustrated my improved latch in association with a door but it is to be understood that this is not to be taken as a limitation of my invention for my latch may be used in connection with any 50 type of a swinging member which moves in

relation to a stationary member. In the drawings, 10 indicates a door which is adapted to be hingedly mounted in a manner not shown in the drawings but which is well understood in the art. This door 10 is adapted 55 to be mounted on the usual jamb construction the fragment of which is illustrated in the drawings and which is indicated by 11. In the embodiment of the invention shown in the drawings, the jamb 11 includes a lip 12 against which the edge 13 of the door is adapted to abut and it is to be understood that the door is to be mounted such that it will swing away from the lip 12 when it is 60 moved to open position.

In the jamb construction 11 at the point best illustrated in the drawings, an opening 14 is provided. This opening 14 may have the latch bolt opening usually provided in 65 jamb constructions although if desired an additional opening may be provided. In the present instant the jamb is recessed as indicated at 15 on the surface on which the opening 14 opens and a face plate 16 is mounted 70 in this recess portion which has an opening 17 provided therein that is adapted to be 75 aligned with the opening 14.

One of the elements of my improved latching device is indicated generically by 17 in 80 the drawings and includes a relatively flat portion 18. Arranged to extend outwardly from the portion 18 from one face thereof is a plate 19. At the end of the portion 18 opposite that from which the plate 19 extends a portion 20 is struck from said portion 18 so as to extend at right angles thereto as is illustrated in Figs. 1 and 2 in the drawings. The outward striking of the portion 20 creates an opening 21 in the member 18. Arranged in the members 18 adjacent the outwardly extending plate 19, a plurality of 85 holes 21 are provided which are preferably arranged in the manner shown best in Fig. 2. The utility of these openings will be described more fully hereinafter.

Adapted to co-operate with the member 17 is a member generically indicated by 23 and this member is formed so as to be substantially U-shaped. It comprises an elongated bight portion 24 and arm portions 25 and 26 90

which are adapted to extend at right angles to said portion 24. Arranged at substantially the mid point of the portion 24 is an opening 27. A leaf spring member 28 is provided which has one end portion thereof connected to the outer end of the arm 25 as indicated at 29 in the drawings. The other end portion 30 of the leaf spring member 28 extends through a recess 31 provided on the outer edge of the arm 26 and this leaf member is connected to the arm 26 adjacent the outer end thereof as indicated at 32.

As is best illustrated in Fig. 1 the leaf spring member 28 is arcuate in form and is arranged such that at substantially the mid point between the end portions 25 and 26 is arranged in juxtaposition to the mid point in the extent of the member 24 an opening 33 is provided in the leaf spring member and a latching member comprising a post 34 and a finger portion 35 which is formed by looping a continuation of the post 34 is arranged such that the post 34 is projected through this opening 33. A collar 36 is disposed around the post 34 and is connected thereto between the leaf spring member 28 and the portion 24 so as to retain the latching member in position.

When positioned in in-operative position so as to be ready for shipping or when not in use the member 23 has the arms 25 and 26 thereof disposed between the arms 21 and 19 of the member 17 and a portion 24 is arranged so as to be disposed opposite from the portion 18 and the portion 30 of the leaf spring member 28 is extended through an opening 37 provided in the portion 19 at the juncture thereof with the portion 18. In this manner the portions 17 and 23 are nested together and this is clearly illustrated in Fig. 4.

When it is desired to install the latching device in latching position with respect to a door or other hingedly mounted member the end portion of the plate 18 is disposed between the edge of the door and the jamb and the lip 20 is inserted into the opening 17 in a manner illustrated in Fig. 1. The door is then moved to closing position which is illustrated in Fig. 1 and the member 23 is arranged such that the outer face of portion 23 is arranged in abutment with the outer face of the portion 18 thus the leg 25 will be disposed in abutment with the face of the door. The finger portion 35 is then gripped so as to retract the bolt member 34 and after the plate member 23 is properly positioned this finger portion 35 is released and therefore the bolt member 34 will pass through one of the openings 22 which are disposed such that one of these openings will always be in position such that the bolt member 34 may pass therethrough. The bolt member 34 is inserted through the opening 22 which will cause tight engagement of the foot portion 25 with the face of the door 10 so that a wedging ac-

tion will be present and this arrangement serves to effectively retain the member 23 in position. Due to the tension of the spring 28, the bolt member 34 will be retained in position and it is therefore apparent that an attempt to move the door 12 such that the portion 13 thereof will disengage the lip 12 will tend to tighten the engagement of the portion 25 with the face of the door and will tend to tighten the engagement of the lip 20 with the wall of the recess and therefore the door will be held against opening movement.

While I have illustrated and described the preferred form of construction for carrying my invention into effect this is capable of variations and modifications without departing from the spirit of the invention. I, therefore, do not want to be limited to the precise details of construction set forth, but desire to avail myself of such variations and modifications as come within the scope of the appended claims.

Having thus described my invention what I claim as new and desire to protect by Letters Patent is:

1. A latching device including a substantially flat plate, said plate having projections extending from one face thereof in spaced relation with the ends and having a plurality of openings formed therein adjacent one of said projections, a substantially U-shaped member including an elongated bight portion, a spring member having portions connected to the limbs of said U-shaped member and having the intermediate portions thereof disposed toward said bight portion, a connecting member, means for attaching said connecting member to said spring member whereby when said plate and the bight portion of said U-shaped member are arranged in abutting relation said spring member will force said connecting member through a selected one of said openings.

2. In combination with a door and a jamb therefor, means for latching said door against opening movement including a plate having a leg extending from one face thereof, said plate being disposed between said door and said jamb with said projection in an opening in said jamb, a substantially U-shaped member including an elongated bight portion, a leaf spring having the end portions thereof secured to the ends of the limbs of said U-shaped member and having the intermediate portions thereof disposed toward said bight portion, said bight portion having an elongated transversely extending slot formed therein, said spring member having an elongated transversely extending slot formed therein in alignment with said first named slot, a securing member, said securing member including a post portion extended through said slots, means for connecting said securing member to said spring member whereby said spring member will urge said

securing member in the direction of said bight portion, said plate having a plurality of openings formed therein whereby when said U-shaped member is disposed with one of the limb portions in abutment with the face of said door said securing member may be extended through one of said openings to interconnect said plate and said U-shaped member to prevent opening movement of said door.

10 In testimony whereof I affix my signature.
FREDERICK AVERY COX.
